OVERHEAD SYSTEM FOR SPRAY PAINTING

Charles E. Martindale, Woodland, Calif.

Application February 26, 1954, Serial No. 412,785

8 Claims. (Cl. 299—86)

This invention relates to spray-painting equipment or systems for cars or other portable devices which need painting and which can be removably placed in a spray booth; the present application being a continuation-in-part of my now abandoned application, Serial No. 332,489, filed January 21, 1953.

The principal object of my invention is to provide a painting system which includes an overhead swingable boom from which the supply of paint and the spray hoses are supported, and which boom is arranged so that, with a relatively short hose unit, a car may be completely spray painted in an efficient manner and with a minimum of physical effort and time on the part of the operator.

An objectionable feature of previous spray-painting equipment, namely, a long stretch of floor-supported hose which must be dragged around and which tends to become entangled with the wheels of the car or other object, is, therefore, eliminated.

Another object of the invention is to mount the paint containing pot on the swinging boom in removable association therewith, and so that said pot, when so mounted, is connected to a source of compressed air as well as to the hose unit which carries the spray gun. In this manner, the need of a paint cup attached directly to the gun, and whose weight is carried by the operator, with resultant fatigue and possible loss of control, is avoided.

Also, a much larger supply of paint may thus be carried without having to stop and refill the pot and without any added weight being placed on the operator, so that a complete spray-painting job may be performed without any stops being necessary for paint-supply replenishing.

It has been found that heated paint provides an easier, faster, and more trouble-free means of spray application than was had with cold paint.

A further object of the invention, therefore, is to provide a paint pot which is arranged to be heated and which is so thoroughly insulated that once heated, it will retain its heat for a sufficient time to enable a complete spray-painting operation to be carried out without re-heating of the paint being necessary and so that no hot surface is exposed within the spray booth.

Such heating is accomplished by electrical means, and since it would be dangerous—because of possible sparks and the volatile nature of the paint fumes—to thus heat the pot within the necessarily closed spray booth, it is another object of the invention to provide means for supplying heat to the paint pot from a point outside the spray booth while providing means on the pot for both detachably connecting the pot to a source of heat and subsequently to the boom in supported relation therewith.

Still another object of the invention is to provide a spray-painting system which is practical, reliable, and durable, and one which is exceedingly effective for the purpose for which it is designed.

These objects are accomplished by means of such structure and relative arrangement of parts as will fully ap-

pear by a perusal of the following specification and claims.

In the drawings:

Fig. 1 is a side elevation of the improved equipment of the system, as mounted in a spray booth and in operation.

Fig. 2 is an enlarged end elevation of the paint pot and its boom-mounting connection, taken substantially on line 2—2 of Fig. 1.

Fig. 3 is a fragmentary enlarged vertical section of the boom and its pivot mounting structure.

Fig. 4 is a side elevation of the paint pot detached, partly in section and with the cover removed.

Fig. 5 is a side elevation of the paint pot cover and parts connected thereto; the cover being detached from the pot and partly in section.

Fig. 6 is an elevation, partly in section, of the fixed switch and connector unit for the paint pot, by means of which electric heat is supplied to the paint pot; the latter being shown as connected to said unit.

Referring now more particularly to the characters of reference on the drawings, the conventional spray booth 1, in which a car 2 to be spray-painted is disposed, includes a ceiling 3 supported by joists 4.

The improved spray-painting system or equipment, which is mounted in such booth, is constructed as follows:

Mounted centrally of the ceiling on adjacent joists 4 is a rigid horizontal frame 5 which supports, by suitably braced clamping collars 6, a depending sleeve 7 which extends a very short distance only below the ceiling.

Turnably projecting through the sleeve is a tubular spindle 8 having a cap 9 resting on the upper end of the sleeve 7.

The spindle 8 depends below the sleeve some distance, and projecting from and rigid with the depending portion of the spindle is a boom, indicated generally at 10. This boom includes a pair of vertically spaced, generally parallel tubular arms 11 preferably disposed with a slight downward slope and connected at their outer end by a vertical sleeve 12.

The total length of this portion of the boom is somewhat less than half the width of the spray booth which is customarily longer than it is wide.

The boom also includes a relatively short extension 13 which includes a spindle 14 turnable in the sleeve 12, a lower horizontal arm 15 projecting from the lower end of the spindle, and a vertical sleeve 16, open at its lower end, upstanding from the outer end of arm 15.

The spindle 8 is arranged for unrestricted rotation in sleeve 7, but the spindle 14 may only turn 90 degrees from an aligned position of the extension 13 with the main boom arms 11; a rotation-limiting pin and notch unit 17 being provided on the spindle 14 and sleeve 12 for this purpose.

The paint pot, indicated generally at 18, and which is of special construction as hereinafter described, includes a rigid upwardly projecting stem 19 on one side and which removably projects into sleeve 16 from its lower end so that the pot is held in an upstanding position beyond the extension 13, as shown in Fig. 1.

To removably retain the stem in place, said stem is formed with a lug 20 intermediate its ends, non-turnably fitting in a hood 21 formed laterally with and extending upwardly from the lower end of the sleeve 16. The lug is engaged from below by a releasable holding arm 22 pivoted in the hood and projecting below the same for manipulation (see Fig. 2).

The paint pot 18 comprises an outer shell 23 to which the stem 19 is connected, an inner paint receiving receptacle 24 spaced from the shell 23, and an intermediate

shell 25 spaced (except at the top) from shell 23 and receptacle 24.

At their upper end, the shells converge to the rim of the receptacle and are clamped together by the depending rim flange 26 of the receptacle, as shown in Fig. 4.

The space between the shells 23 and 25 is filled with heat insulating material 27, while a suitably insulated thermostat-controlled electric heating element, indicated diagrammatically at 28, is disposed in the space between shell 25 and receptacle 24.

The lead wires 29 extend from element 28 through the stem 19 to the upper end thereof, connecting to terminals 30 exposed at the upper end of the stem for engagement with cooperating contacts of a current supplying unit, as will hereinafter be described.

The pot 18 includes a heat-insulated cover 31 removably seated on rim flange 26 and held in place with a pressure tight fit by suitable screw-clamp units 32 mounted on flange 26.

Secured on the cover and communicating with the interior thereof is a double-ended fitting 33, and another fitting 34 on the cover connects to a depending tube 35 of a length such as to depend nearly to the bottom of receptacle 24. The fitting 33 includes a pressure-regulating valve unit therein.

A flexible hose 36 is releasably coupled, as at 37, to one end of the fitting 33 and extends thence through an opening 38 in the upper boom arm 11 and along said arm and into the tubular spindle 8 to connection with a swivel fitting 39 mounted in the cap 9, as shown in Fig. 3.

Another hose or pipe 40, leading from a source of air pressure, is connected to the fitting above the cap.

Another length of hose 41 is connected to the other end of fitting 33 and extends to a hand-operated spray gun 42 of conventional form.

Another similar length of hose 43 extends from fitting 34 to the gun; the hoses 41 and 43 being only long enough that the gun may be manipulated over a comparatively small area of the car without any movement of the boom.

Mounted on a wall of the shop outside but adjacent the booth, as shown in Fig. 1, is a bracket 44 on which a vertical sleeve 45 is mounted; this sleeve being open on its lower end and the same diameter as sleeve 16 so that the stem 19 of the paint pot may be projected into said sleeve 45.

The lug 20 of said stem is then engaged by a holding lever 46 arranged the same as lever 22. When the stem 19 is so mounted, the terminals 30 thereon engage a pair of spring-pressed contacts 47 mounted in the upper portion of the sleeve 45, as shown in Fig. 6.

These contacts are connected to the wires 48 of an extension cord 49 which extend to a junction box 50, or the like. Since the contacts and terminals, when engaged, are completely and deeply enclosed, there is no chance of any sparks being exposed to the outside of the sleeve as the contacts and terminals are engaged or separated.

In operation, the paint supply in receptacle 24 is first heated by inserting stem 19 into sleeve 45 until the paint has attained the desired heat, the cover remaining on the pot; the hose 36 being disconnected at fitting 33. The pot is then mounted on the boom extension, and upon connecting the air hose 36 to fitting 33 and turning on the air pressure in said hose, the spray painting operation may be started and continued to completion of the job without any stops for paint replenishing being necessary since receptacle 24 is of ample size to hold enough paint for any one car and, as previously stated, the pot construction is such that the paint will retain its heat for the duration of such complete painting operation.

The articulated boom enables the paint pot to be shifted both lengthwise and laterally of the car as the

painting progresses; the extension 13 turning about the sleeve 12 as may be necessary by reason of the relatively narrow width of the spray booth or because of the desirability of maintaining the pot as nearly overhead to the area being painted as is practicable since the hoses 41 and 43 are purposely not overly long. The extension can thus be turned about the sleeve 12, or the whole boom may be turned about the sleeve 9, by merely pulling on the hose one way or the other.

The boom is thus long enough to reach from end to end of the longest car, yet may be adjusted to enable the relatively close-together sides of the car to be conveniently painted.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A spray painting system for a spray booth comprising an elongated substantially horizontal boom, means pivotally supporting the boom at one end from the ceiling of the booth for rotation about a vertical axis, a paint supply pot supported from the outer end of the boom and having a hose gun unit connected thereto, and means to supply compressed air to the pot; the boom including a main portion and an extension, and means pivoting the extension on said main portion of the boom for rotation about a vertical axis, the pot being mounted on the outer end of the extension.

2. A spray painting system for a spray booth comprising an elongated substantially horizontal boom, means pivotally supporting the boom at one end from the ceiling of the booth for rotation about a vertical axis, a paint supply pot having a hose and spray gun unit connected thereto, means to supply compressed air to the pot, and means removably mounting the pot on the outer end of the boom; the pot mounting means comprising a sleeve on the boom at its outer end, a stem rigid with and projecting from the pot and extending into the sleeve, and releasable latch means between the sleeve and stem.

3. A spray painting system for a spray booth comprising an elongated substantially horizontal boom, means pivotally supporting the boom at one end from the ceiling of the booth for rotation about a vertical axis, a paint supply pot having a hose and spray gun unit connected thereto, a compressed air supply conduit detachably connected to the pot, and means removably mounting the pot on the outer end of the boom; the pot mounting means comprising a vertical sleeve on the boom at the outer end thereof and open at its lower end, a vertical stem on one side of the pot and rigidly connected at its lower end thereto, the stem sliding into the stem from the lower end thereof, a lug on the stem intermediate its ends, a lateral hood on and open to the sleeve into which the lug slidably and non-turnably projects, and a catch arm mounted in the hood and arranged to releasably engage under the lug in supporting relation.

4. A spray painting system for a spray booth comprising an elongated substantially horizontal boom, means pivotally supporting the boom at one end from the ceiling of the booth for rotation about a vertical axis, said means including a fixed sleeve and a tubular spindle turnable in and depending from the sleeve, the boom being rigid with an projecting from the spindle below the sleeve and including a tubular arm communicating with the interior of the spindle; a paint supply pressure pot supported from the outer end of the boom, and means to supply compressed air to the pot and including an air

supply conduit, means swivelly connected to the conduit at one end to the upper end of the spindle, and an air hose connected to the pot and projecting into the arm adjacent its outer end and extending along and within the arm and spindle to a connection with the swivel connection.

5. A structure as in claim 4, with means detachably mounting the pot on the boom, and a detachable connection between the air hose and pot.

6. In an overhead spray-painting system the combination with a boom having a sleeve at its outer end, a paint pot having an electric heating element incorporated therewith, and a stem on one side of the pot adapted to enter and to be detachably supported from the sleeve; of means to supply electric heat to the element and including another sleeve fixed separate from the boom sleeve and adapted to receive the stem, electrical terminals on the outer end of the stem connected to the element, and electrical contacts arranged for connection to a source of electric power mounted in said other sleeve to engage the terminals when the stem is disposed within said other sleeve.

7. In combination, a paint supply pot including a paint receiving receptacle, an outer shell, an electric heating element between the shell and receptacle, a stem project-

5

10

15

20

25

ing from and rigid with the shell, and electrical terminals exposed on the outer end of the stem and connected to the element; a fixed sleeve into which the stem slidably projects, releasable means retaining the stem in a predetermined position within the sleeve, and electrical contacts arranged for connection to a source of electric power mounted in the sleeve and engaging the terminals when the stem is in said position in the sleeve.

8. A spray painting system, for a spray booth, comprising an elongated substantially horizontal boom, means pivotally supporting the boom at one end from the ceiling of the booth for rotation about a vertical axis, the boom including a main portion and an extension, means pivoting the extension on said main portion for rotation about a vertical axis, and a pressure painting apparatus including painting hose and spray gun unit depending and supported from the outer end of the extension.
